UNITED STATES PATENT OFFICE.

GEORGE W. DONLEY, OF CLEVELAND, OHIO, ASSIGNOR TO THE DONLEY BROTHERS COMPANY, OF CLEVELAND, OHIO, A CORPORATION.

DESIGN FOR AN ANDIRON.

Application filed December 3, 1928. Serial No. 29,096. Term of patent 14 years.

To all whom it may concern:

Be it known that I, GEORGE W. DONLEY, a citizen of the United States, residing at Cleveland, in the county of Cuyahoga and State of Ohio, have invented a new, original, and ornamental Design for Andirons, of which the following is a specification, reference being had to the accompanying drawing, forming

part thereof, and in which the figure is a front view in perspective of the article, showing my new design.

I claim:

The ornamental design for an andiron, substantially as shown.

GEORGE W. DONLEY.
